(57) **CLAIM**

The ornamental design for a “highlighter,” as shown and described.

DESCRIPTION

FIG. 1 is a perspective view as seen from the top, front and right side of a highlighter showing my new design; FIG. 2 is a right elevational view, the left elevational view being a mirror image thereof; FIG. 3 is a front view thereof; FIG. 4 is a rear view thereof; FIG. 5 is a top plan view thereof; FIG. 6 is a bottom view thereof; and, FIG. 7 is a perspective view of a highlighter of FIG. 1 with the marking tip exposed and the cap positioned on the bottom of the highlighter barrel. The broken line showing a tip of a highlighter is for illustrative purposes only and forms no part of the claimed design.
